Primary Examiner — Lucy Lieberman(74) *Attorney, Agent, or Firm* — Betts, Patterson & Mines, P.S.**CLAIM**

The ornamental design for a clock face, as shown and described.

DESCRIPTION

The sole view is a front elevation of a clock face showing my new design.

The broken lines in the drawing are used to show portions of a clock and hands that do not form part of the claimed design. The front of the claimed clock face is flat.
